ALEXANDER MONCRIEFF, OF WOOLWICH, ENGLAND.

Letters Patent No. 83,873, dated November 10, 1868; patented in England, June 4, 1866.

IMPROVEMENT IN GUN-CARRIAGES.

The Schedule referred to in these Letters Patent and making part of the same.

To all whom it may concern:

Be it known that I, ALEXANDER MONCRIEFF, of Woolwich, England, have invented an "Improved System of Mounting and Working Ordnance;" and I do hereby declare that the following is a full and exact description of the said invention, reference being had to the accompanying drawing, and to the letters marked thereon; that is to say—

The object of this invention is to afford protection to guns in batteries, and to the men serving them, and at the same time to prevent the violent strains put upon the carriage and platform by the recoil.

The invention consists in supporting the gun, in an elevated position, upon a framing or other contrivance constituting a double-ended lever, so arranged that, while the gun is connected to one end of such lever, and a corresponding balance-weight or equivalent force is attached or connected to the other end thereof, the fulcrum of the lever, on firing the gun, is caused, by the motion imparted thereto by the recoil, to shift nearer to the gun and farther from the balance-weight or force, while at the same time the gun itself, in moving with the lever, sinks down into a position below the level of the parapet, so as to enable the detachment to reload it. By such shifting of the fulcrum, the statical momentum of the balance-weight is made to preponderate so greatly over that of the gun that it will, when allowed free action, after loading the gun, raise the same again into its original position.

This I effect by mounting the gun on a carriage which is supported by two wheels, curved rollers, or segment-blocks, which I call "elevators." These elevators have a rolling motion on the rails which support them, and are connected together, by a transverse axle, near their periphery, on which the gun-carriage rests.

To the opposite ends of these elevators, (or those ends which are lowest when the gun is in the firing-position,) I attach a counter-weight, spring, or other force of equivalent power, as a balance to the gun, the point of contact between the "elevators" and the rails which support them being the moving fulcrum above referred to.

When the gun is fired, the transverse axle, which supports the gun, and which I call the gun-axle, descends in a cycloidal curve until the action of the counter-weight or spring of equivalent power exhausts the energy of the recoil. When the recoil is ended, the gun-axle will be at its lowest position, and the gun which that axle supports will be in the loading-position. In that position it is held by a check or pawl. When that check is removed, the action of the counter-weight, or spring of equivalent power, will tend to bring the gun back to the firing-position, by causing the elevators to roll forward by the strain thus brought upon them.

In carrying out this invention, I prefer to support

the rear of the gun-carriage in one of three ways, viz, first, by fixed guides, in or on which the rear of the gun-carriage will slide; second, by elongating the gun-carriage into a trail, which would be supported by a transverse bar at the back of the frame; third, by radius bars, centring below the frame.

The accompanying drawing shows one of the various arrangements of which my invention is susceptible.

The gun A is supported upon the carriage B, which is itself carried by the "elevators" C, situated on each side thereof, the carriage being connected to the elevators by means of the transverse axle D.

The "elevators," which in this case are segment-blocks, carry between them, at their lower ends, a counterweight, E, which is slightly heavier than the gun, so as to hold the same with stability in the raised position for firing indicated by the black lines.

The centre of gravity between the counter-weight and the gun is also, by preference, the centre for the radius with which the curved portion *c c* of the back surface of the elevators is struck, while the upper portion of the back surface is formed with a much flatter curvature.

The "elevators" rest upon the traversing-platform F, turning upon a central pivot, G, and running upon racers H.

On firing the gun, the recoil causes the elevators to roll back upon the platform, and thus to bring the gun down into the position indicated by the red lines, the gun being, during such motion, maintained in its more or less horizontal position, by causing the lower end of the carriage B, provided with rollers *b*, to move down guide-rails I, carried by the framing J from the platform F.

So long as the elevators roll upon their curved parts *c c*, but little resistance will be offered to the downward motion of the gun, because it will be evident that as the centre of gravity of the gun and counter-weight is at the same time the centre of the circle forming that curvature, it will always remain in one and the same vertical line with the point of that curvature which is in contact with the platform, and which constitutes the moving fulcrum, and therefore there will be no preponderance one way or the other. But so soon as the "elevators" roll on to the flatter curvature, the fulcrum moves to one side of the vertical line, through the centre of gravity, and towards the point of support of the gun, thus increasing the statical momentum of the counter-weight, and decreasing that of the gun, while at the same time the centre of gravity of the whole mass is raised somewhat.

By this means the momentum of the recoil will be gradually absorbed and stored up in the counter-weight, and consequently, as soon as such absorption had been completely effected, the counter-weight would, by virtue of the preponderance, cause the elevators, and with them, the gun, at once to move back into their original

raised position. This, however, is prevented by the pawl K, in gear with the ratchet-wheel L, the spindle of which is supported by the framing J, and carries a pinion, M, in gear with the curved rack N, fixed to the side of the elevator C, which rack is so formed as always to remain in gear with the pinion during the motion of the elevators.

By this arrangement, it will be seen that so long as the pawl K is in gear with the ratchet-wheel L, the gun and elevators will be held in their lowered position, so as to enable the detachment to load the gun. When this has been effected, the pawl K is released from the ratchet-wheel by means of the lever k, when the elevators will rise up with the gun into the position for firing over the parapet O. This upward motion of the elevators is controlled by a friction-brake, P, fixed on the spindle of the pinion M, and actuated by the handle p.

In order to prevent the elevators from shifting out of their correct position, racks Q are fixed on the platform F, into which similar racks or studs on the elevators gear as these roll up and down.

Steps R R are provided, for aiming before firing. Having thus described the nature of my invention,

and one of the various methods of carrying the same into practice, I wish it to be understood that I in no way limit myself to the arrangement shown by the accompanying drawing, as my improved system may be carried out by a variety of different arrangements, and will have to be specially adapted, according as the guns are to be applied as fort-guns, siege-guns, for floating batteries, &c.; but

What I claim, is—

The before-described system of mounting and working ordnance, whereby the gun is supported upon a moving fulcrum, which, on the firing of the gun, is caused to shift nearer to the gun, and farther from a counter-weight, spring, or other force, while at the same time the gun is brought into a lowered position for reloading, and is then automatically raised into position for firing.

In testimony whereof, I have signed my name to this specification, in the presence of two subscribing witnesses, this 27th day of March, 1868.

A. MONORIEFE.
